UNITED STATES PATENT OFFICE.

THEODOR R. A. WEBER, OF NEW YORK, ASSIGNOR TO HIMSELF, JOHN H. PENDLETON, OF BROOKLYN, AND ROBERT I. SLOAN, CORNELIUS TIERS, AND ALEXANDER H. TIERS, OF NEW YORK, N. Y.

TUBULAR IRON RAILING.

SPECIFICATION forming part of Letters Patent No. 340,263, dated April 20, 1886.

Application filed December 26, 1885. Serial No. 186,693. (No model.)

To all whom it may concern:

Be it known that I, THEODOR R. A. WEBER, of the city and State of New York, have invented an Improvement in Tubular Iron Railings, of which the following is a specification.

Iron railings have been made of tubes screwed together, with bends and elbows similar to those employed with gas-pipes; but difficulty has arisen with connections of this character, because the tubular rails cannot be introduced in long lengths passing through and connected with several intervening posts and with screw-connections, the posts and rails have to be connected before the posts are secured in place, and it is difficult to place the posts in a vertical position.

My improvements are made for facilitating the construction of the iron fence or railing by making the tubular posts and their tubular connections complete, so that they may be set in position and then the tubular rails passed through them and afterward clamped in place. This allows for the use of rails of any desired length, so that the fence is rendered strong and durable, and the posts can be placed at any desired distances apart without changing the lengths of the tubular rails.

In the drawings, Figure 1 is an elevation representing part of a fence with tubular posts and round rails. Fig. 2 shows a portion of an iron fence or railing with tubular posts and square rails. Fig. 3 is a section in larger size showing the top coupling and an intermediate coupling on the post. Fig. 4 is an elevation of portions of a post with the rails and couplings in section at the line *xx*, Fig. 3. Fig. 5 is a section of the couplings at one of the end posts. Fig. 6 is a section through the coupling and square rail at the line *yy*, Fig. 2. Fig. 7 is an inverted plan of one of the couplings, the post being in section; and Fig. 8 is a detached view showing the rail at an inclination to the post. Figs. 3 to 7, inclusive, are in larger size than Figs. 1 and 2.

Each post is composed of two or more sections of metal tubing, A, with screw-threads cut upon their ends, and the lower end of the lower section is screwed into a base, B, of metal, which may be of any known or desired char-

acter. Where the railing is to be attached to wood-work, this base B will usually be in the form of a plate attached by screws to the wood-work. If the railing is to be set in the earth, the base B will be a block of metal, stone, or other suitable material.

Between the tubular sections A A there are junction-pieces C, formed with sockets 1 2 for the respective screw ends of the tubular sections A, and with a transverse opening passing through each intersecting piece for the passage of the rail D. If this rail D is round, the opening will correspond thereto. If the rail D is polygonal, as shown in Figs. 2 and 6, the opening in the intersection-piece will be of the same shape. The projecting end portions of the intersection-pieces are not made as complete cylinders or square sockets, but they are slotted longitudinally, as shown at 4, and provided with ears 5 for the passage of screw-bolts or rivets E. If the posts are composed of two tubular sections A, there will be one intersection-piece C in each post. If there are three tubular sections A, there will be two intersection-pieces C and two lines of rail D. At the top of each post there is a cap-piece, F. This is made to correspond to the intersection piece C, except that there is no coupling 1 upon the same, the top of the cap-piece being smooth, as shown in the drawings, and there are the ears 5 at each side of the longitudinal incisions 4, and the bolts or rivets E passing through the ears. It is now to be understood that the openings through the cap-pieces and intersection-pieces are to be of a size that will allow the rails D to be slipped endwise through the same after the complete posts have been set in place. It is preferable to place the posts at such distances apart that the extreme ends of the rails D will be within a cap or intersection piece, so as to avoid any other connection between one rail and the next, and usually it is preferable to pass the rails into their places before setting the end posts. I have shown one of the end posts at the right-hand end in Fig. 1 and sectionally in Fig. 5, the junction-piece C' being similar to the junction-pieces C, except that the opening for the rail is provided at one side only, and the cap-piece

F' is similar to the cap-piece F, except that the opening for the rail is only at one side, and the cap-piece is made as a bend or elbow, as seen in Fig. 5. After the parts of the railing have been placed in position the bolts or rivets E are inserted and tightened up, so as to spring the open ends of the respective cap-pieces and intersection-pieces and clamp and confine the rails firmly in place.

10 It is preferable to make the openings between the ears 5 and the socket 2 wider, so as to allow the metal to spring more easily under the action of the rivets or bolts E, and usually it is preferable to make use of larger tubes for the posts than for the rails, as shown. The portions of the junction-pieces that surround and are clamped to the rails should be thinner on the upper side than at the bases of the ears, to render the strength of the parts 15 more uniform.

15 Railings for staircases can be made in the manner afore described; but the openings for the rails in the junction and cap pieces must be made at an inclination to the sockets receiving the posts, as shown in the detached view, Fig. 8.

I claim as my invention—

1. The metallic posts formed of the tubular sections A and the intersection-pieces C

and cap-pieces F, permanently screwed together, such intersection-pieces and cap-pieces being slotted at 4, and provided with ears 5, in combination with the rails D, passing entirely through the respective intersection-pieces and cap-pieces, and the bolts or rivets 35 E, by which the rails are clamped, substantially as set forth.

2. The end posts for the iron railing, formed of the tubular sections A, intersection-pieces C', each having an opening at one side for the 40 reception of the rail, the cap-pieces F', formed as a bend, there being the slots at 4, and ears at 5, in combination with the rails D and clamping screws or rivets E, substantially as specified.

3. The intersection-pieces C, having screw-sockets for the reception of the post-sections, and openings for the passage of the rails, and the ears 5 for the rivets or bolts to clamp the rails, there being enlarged openings in the 50 junction-pieces between the ears and the socket, substantially as set forth.

Signed by me this 10th day of December, A. D. 1885.

THEODOR R. A. WEBER.
